MACHINE FOR CLEANING WINDOW SHADES

Peter F. Nardulli and Michael J. Nardulli,
Chicago, Ill.

Application December 13, 1933, Serial No. 702,138

12 Claims. (Cl. 15—40)

Our invention relates to an improved machine for cleaning window shades, by which the shade may be placed in the machine without removing it from its roller, and cleaned on both sides before removing the shade from the machine.

More specifically, our invention consists of a rotary drum for receiving the shade to be cleaned, which drum is mounted in a tank containing the liquid employed to clean the shade, and brushing means for removing the dirt and foreign matter from the shade in its wetted condition, suitable gearing and clutch mechanism being provided to rotate the drum first in one direction and then in the other direction, at the will of the operator, so that both sides of the shade may be cleaned without removing the shade from the machine. By our invention, we also provide improved devices for retaining the shade roller in a recess in the drum of the machine, so that the shade need not be removed from the roller during the cleaning of the shade, said devices being adjustable to engage and hold rollers of different desired lengths corresponding with different widths of shades, within the capacity of the machine.

Our invention will best be understood by reference to the accompanying drawing illustrating a preferred form of our machine, in which

Fig. 1 illustrates our machine in front elevation,

Fig. 2 illustrates our machine in end elevation, Fig. 3 is a plan view of a part of one end of the machine, to illustrate the gearing employed to drive the brushing mechanism,

Fig. 4 is a fragmentary plan view to an enlarged scale, of a part of the drum of the machine, illustrating the roller retaining devices, and

Fig. 5 is an end elevation of the parts shown in Fig. 4.

Similar numerals refer to similar parts throughout the several views.

As shown in Figs. 1 and 2, a cylindrical drum 10 is mounted for rotation on and secured to a shaft 11, extending axially through said drum, which shaft is supported in bearings 12, 12 for rotation by the gearing below described. The bearings 12, 12 are supported by a framework collectively designated 13, which framework also supports a semi-cylindrical tank 14 around the lower portion of the drum 10.

The drum 10 is preferably made of sheet metal, its ends and side walls being secured together in any suitable manner, for example by welding, to completely enclose the drum so that the water or other cleaning liquid employed in the tank 14,

will not find its way into the drum. The tank 14 is preferably made of sheet metal and is provided with end and side walls around the lower part of the drum 10, to hold the cleaning liquid and cover the lower part of the outer surface of the drum 10. Suitable reinforcing bars may be used as desired, in connection with these sheet metal structures, as indicated for example, for the ends of the drum 10 at 10a.

The shaft 11 is extended at one end beyond its adjacent bearing 12, and has rigidly secured to it a bevel gear 15 meshing with bevel gears 16 and 17 mounted on a vertical shaft 18 supported in suitable bearings 19, 20 and 21 carried by the framework 13, the bearings 19 and 20 also serving to hold the bevel gears 16 and 17 in mesh with the bevel gear 15. The bevel gears 16 and 17 are mounted for free rotation relatively to the shaft 18, unless restrained from said relative rotation by the clutch mechanism carried by said bevel gears and said shaft as follows: The bevel gear 16 is provided with a downwardly extending hub 16a forming one member of a clutch for co-operation with a second clutch member 22 rigidly secured to the shaft 18, said shaft being movable vertically in its supporting bearings and also in the bevel gears 16 and 17, to engage and disengage the clutch members 16a and 22. The bevel gear 17 is provided with an upwardly extending hub 17a constituting one member of a second clutch for engagement with a co-operating clutch member 23 rigidly secured to the shaft 18, the relation of the clutch members 22 and 23 being such that when the clutch members 16a and 22 are in engagement with each other, the clutch members 17a and 23 are in disengaged relation, the relation of the clutch members 22 and 23 to each other being preferably such that for an intermediate position of the shaft 18 vertically, neither the clutch members 16a and 22 nor the clutch members 17a and 23 are in engagement with each other, for which condition, the shaft 18 may rotate, without rotation of the drum 10. The shaft 18 below the bearing 20, has rigidly secured to it, a grooved collar 24 containing the ends of an operating yoke 25 rigidly secured to the upper end of an operating rod 26 extending vertically downwards from the yoke through a supporting and guiding bracket 27 supported in turn by the framework 13. The lower end of the rod 26 is pivotally connected with one end of a lever 28 pivotally supported at 29 by a bracket 30 which is supported in turn by the framework 13 of the machine, the other end of said lever

28 being pivotally connected with the rear end of a treadle 31 pivotally supported at 32 by brackets 33, 33 which are in turn supported by the framework 13 of the machine. The front end of the treadle 31 is provided with a treadle pad 34 conveniently located for engagement by the foot of the operator of the machine. A spring 35 is disposed between the yoke 25 and the bracket 27 to hold the shaft 18 and the parts connected therewith, in their uppermost position, when the treadle pad 34 is not depressed.

As a result of the construction just described, when the operator depresses the treadle pad 34, the rod 26 is moved downwardly, thereby disengaging the clutch members 16a and 22, and for continued downward movement of the treadle pad 34, engaging the clutch members 17a and 23, which, as a result of the relation of the bevel gearing illustrated, reverses the direction of rotation of the drum 10 for continuous rotation in the same direction of the shaft 18. By depressing the treadle pad 34 to its mid-position, the shaft 18 is rotatively disengaged from both of the bevel gears 16 and 17, to stop rotation of the drum 10, without interrupting the rotation of the shaft 18, to permit placing a shade in the machine or removing a cleaned shade therefrom.

The shaft 18 is extended below its bearing 21 to support a bevel gear 36 below said bearing and 30 in mesh with a second bevel gear 31 carried by a horizontal shaft 38 supported in a bearing 39 from the framework 13, and carrying at its other end a worm wheel 40, which worm wheel meshes with a worm 41 carried by the shaft of a motor 35 42 employed to drive the drum 10 and also the brushing mechanism of the machine. The bevel gear 36 is splined on the shaft 18 so that the shaft may move axially through the gear, but be incapable in any of its positions relatively to 40 said gear, of angular movement relatively to said gear.

The other end of the shaft 11 is extended beyond its adjacent bearing 12, and has secured thereto a wheel 43 connected by a chain or equivalent belt 44, with a second wheel 45 preferably of considerably smaller diameter than the wheel 43 and carried by a short shaft 46, the other end of which has secured thereto a gear 47 meshing with a pinion 48 illustrated in Fig. 3, which pinion is secured to one end of a horizontal shaft 49 extending across the machine parallel with the drum 10 to support and drive a rotary brush 50, the bristles of said brush being moved rapidly across the surface of the drum 10 or across the 55 surface of the shade carried by the drum, when the drum is rotated. As illustrated in Fig. 3, the shaft 46 is supported in a bearing 51 carried by the framework 13 and the shaft 49 is supported in a bearing 52 carried by said framework, it being understood that the other end of the shaft 49, which extends the entire length of the machine, is similarly supported by a similar bearing at the other end of the machine. The gear 47 is purposely considerably larger than the pinion 50 48 and as a result, the brush 50 is rotated at a high rate of speed for slow rotation of the drum 10, to the end that the washing and cleaning effect produced by the brush 50 shall be a maximum, and at the same time permitting relatively slow rotation of the drum and the shade carried thereby.

The drum 10 as shown in Figs. 2 and 5, has formed longitudinally in its outer side surface, a groove or depression 53 preferably having side walls to the lower portions of which, guide bars

54 are secured, which bars extend longitudinally of the groove 53 and are substantially parallel with the bottom wall of said groove. The bars 54, as more clearly shown in Fig. 4, support sliding blocks 55, 56 and 57 for holding a shade roller 58 in said groove. The block 55 comprises a base portion and an outwardly extending flange portion 55a provided with an opening to receive one of the end supports of the roller 58. The base portion of the block 55 is provided with edge grooves which are a sliding fit on the bars 54, 54 and said block is also provided with a thumb screw 59 for clamping the block in desired position on the bars 54, 54. The block 57 is constructed similarly to the block 55, excepting that it does not directly support the other end of the roller 58, but has extending from it towards said roller, two guide rods 60, 60 which extend through the block 56 and are provided with heads outside of said block. Springs 61, 61 are located around 20 the rods 60, 60 between the blocks 56 and 57, to separate the blocks as far as the heads on the rods 60, 60, or the adjustment of the devices in supporting the roller 58, will permit. The block 57 is provided with a flange portion 57a 25 and with a thumb screw 62 for securing it in any desired position on the bars 54, 54, and the block 56 is of substantially the conformation of the flange portion 57a of the block 57, and is provided with an aperture in its outer part to receive the end support of the roller 58 remote from the block 55. The devices described for mounting the roller 58 in the groove 53, permit the roller to be mounted in any desired position longitudinally of the groove, and also permit the 30 mounting in the groove of rollers of different lengths within the capacity of the machine, it being understood that the drum 10 is somewhat longer than the length of the longest roller to be mounted on the drum and therefore than the 35 width of the widest shade to be cleaned by the machine. The roller mounting devices also provide a convenient means for cleaning a plurality of shades of the same width, for after the blocks 55 and 57 have been secured in desired position 40 in the groove 53 for the particular length of roller and width of shade to be handled by the machine, the rollers may be inserted between and supported by the blocks 55 and 56, one after another, by movement of the block 56 relatively 45 to the block 57 against the action of the springs 61, 61, thus materially expediting the work of inserting and removing the rollers.

With the roller 58 placed in the groove 53 as described, the shade 63 is drawn around the 55 surface of the drum 10 by the rotation of the latter, until its entire length rests against the drum, the drum being made of a circumference somewhat greater than the length of the longest shade to be cleaned by the machine. The supports for the roller 58 permit its free rotation until the shade 63 is entirely unwound from the roller, and continued rotation of the drum in a direction to wrap the shade 63 around the drum, moves the shade past the brush 50, so that 60 all parts of the surface of the shade which is then outermost, are thoroughly cleaned by the scrubbing action of the brush. The rotation of the drum in the direction referred to, is continued until the cleaning action on the first side 65 of the shade is completed, it being understood that in some cases it may be necessary to give the drum a greater number of rotations than in other cases, before the shade is cleaned, depending upon the degree and manner in which 70 75

the shade is soiled. When the shade is completely cleaned on its outermost surface, the treadle pad 34 is depressed by the operator, which, as above described, reverses the direction of rotation of the drum 10. For this condition, when the free end of the shade is carried into the tank 14, it leaves the drum and the shade collects in folds in the tank until the roller 58 passes through the tank, after which, continued rotation of the drum in its reversed direction, wraps the shade 63 around the drum in the reversed direction and exposes the second side of the shade to the cleaning action of the brush 50, and as before, rotation of the drum is continued until the second side of the shade is completely cleaned.

In Figs. 4 and 5, the shade roller 58 is shown with the shade 63 removed therefrom to more clearly illustrate the construction and relation of the parts in the groove 53. In using the machine, it will be understood that the shade remains attached to the roller as illustrated in Figs. 1 and 2, in the same condition that the shade is used on a window.

The framework 13 is preferably provided with a semi-cylindrical trough 64 to receive the shade in loosely wound condition while it is being first wrapped around the drum 10, and the trough 64 may be employed to receive the cleaned shade when it is removed from the drum, or the shade may be removed from the machine for drying in any other desired manner. To permit the operator to insert a shade roller between the supporting blocks 55 and 56, and to permit the removal of the roller of a cleaned shade from said blocks, the treadle pad 34 is depressed to move the clutch mechanism to its mid portion, for which the rotation of the drum ceases and the shade supporting blocks may be moved as desired to engage or release a shade roller.

The tank 14 may contain any desired cleaning fluid whether it be water and soap or some other detergent, or any other desired solvent for the grease or dirt that may be on the shades to be cleaned, and although the brush 50 is preferably above the level of the liquid in the tank 14, said brush soon becomes completely wetted by the liquid as a result of the carrying of the liquid to it by the shade being cleaned.

While we have shown our invention in the particular embodiment above described, it will be understood that we do not limit ourselves to this exact construction as we may employ equivalents known to the art at the time of the filing of this application without departing from the scope of the appended claims.

What we claim is:

1. In a machine of the class described, the combination of a rotary drum, a tank for containing cleaning liquid around the lower portion of said drum, brushing means adjacent said drum, a driving shaft, gearing between said shaft and said drum for selectively rotating said drum in either of two directions for rotation in a single direction of said shaft, clutch mechanism for selectively connecting said gearing for drum rotation in either desired direction, and devices for mounting a shade roller longitudinally on said drum, whereby a shade attached to said roller may be wrapped around said drum by rotation of the latter and cleaned on both sides by said brushing means for a single mounting of said roller on said drum.

2. In a machine of the class described, the combination of a rotary drum, a tank for containing cleaning liquid around the lower portion of said drum, brushing means adjacent said drum, a

driving shaft, gearing between said shaft and said drum for selectively rotating said drum in either of two directions for rotation in a single direction of said shaft, clutch mechanism for selectively connecting said gearing for drum rotation in either desired direction, and devices for mounting a shade roller longitudinally on said drum, whereby a shade attached to said roller may be wrapped around said drum by rotation of the latter and cleaned on both sides by said brushing means for a single mounting of said roller on said drum, said mounting devices comprising substantially parallel guide bars carried by and extending longitudinally of said drum, blocks mounted for sliding movement on said bars for engagement with the ends of said roller, and clamping devices for holding said blocks in desired positions on said bars.

3. In a machine of the class described, the combination of a rotary drum, a tank for containing cleaning liquid around the lower portion of said drum, brushing means adjacent said drum, a driving shaft, gearing between said shaft and said drum for selectively rotating said drum in either of two directions for rotation in a single direction of said shaft, clutch mechanism for selectively connecting said gearing for drum rotation in either desired direction, and devices for mounting a shade roller longitudinally on said drum, whereby a shade attached to said roller may be wrapped around said drum by rotation of the latter and cleaned on both sides by said brushing means for a single mounting of said roller on said drum, said mounting devices comprising substantially parallel guide bars carried by and extending longitudinally of said drum, blocks mounted for sliding movement on said bars, and clamping devices for holding said blocks in desired positions on said bars, one of said blocks having an aperture for receiving one end support of a shade roller, a second one of said blocks having an aperture for receiving the other end support of said shade roller, a third one of said blocks carrying parallel rods extending through said second block and substantially parallel with said guide bars, and springs on said rods between said second and said third blocks, said clamping devices cooperating with said first and said third blocks.

4. In a machine of the class described, the combination of a rotary drum, a tank for containing cleaning liquid around the lower portion of said drum, brushing means adjacent said drum, a driving shaft, gearing between said shaft and said drum for selectively rotating said drum in either of two directions for rotation in a single direction of said shaft, clutch mechanism for selectively connecting said gearing for drum rotation in either desired direction, and devices for mounting a shade roller longitudinally on said drum, whereby a shade attached to said roller may be wrapped around said drum by rotation of the latter and cleaned on both sides by said brushing means for a single mounting of said roller on said drum, said drum having a longitudinal side depression containing said mounting devices, said depression having an open side freely admitting said roller by lateral movement of said roller.

5. In a machine of the class described, the combination of a rotary drum, a tank for containing cleaning liquid around the lower portion of said drum, brushing means adjacent said drum, a driving shaft, gearing between said shaft and said drum for selectively rotating said drum in either of two directions for rotation in a single

- direction of said shaft, clutch mechanism for selectively connecting said gearing for drum rotation in either desired direction, and devices for mounting a shade roller longitudinally on said drum, whereby a shade attached to said roller may be wrapped around said drum by rotation of the latter and cleaned on both sides by said brushing means for a single mounting of said roller on said drum, said mounting devices comprising substantially parallel guide bars carried by and extending longitudinally of said drum, blocks mounted for sliding movement on said bars for engagement with the ends of said roller, and clamping devices for holding said blocks in desired positions on said bars, said drum having a longitudinal side depression containing said guide bars and said blocks.
6. In a machine of the class described, the combination of a rotary drum, a tank for containing cleaning liquid around the lower portion of said drum, brushing means adjacent said drum, a driving shaft, gearing between said shaft and said drum for selectively rotating said drum in either of two directions for rotation in a single direction of said shaft, clutch mechanism for selectively connecting said gearing for drum rotation in either desired direction, and devices for mounting a shade roller longitudinally on said drum, whereby a shade attached to said roller may be wrapped around said drum by rotation of the latter and cleaned on both sides by said brushing means for a single mounting of said roller on said drum, said mounting devices comprising substantially parallel guide bars carried by and extending longitudinally of said drum, blocks mounted for sliding movement on said bars, and clamping devices for holding said blocks in desired positions on said bars, one of said blocks having an aperture for receiving one end support of a shade roller, a second one of said blocks having an aperture for receiving the other end support of said shade roller, a third one of said blocks carrying parallel rods extending through said second block and substantially parallel with said guide bars, and springs on said rods between said second and said third blocks, said clamping devices cooperating with said first and said third blocks, said drum having a longitudinal side depression containing said guide bars and said blocks, said depression having an open side freely admitting said roller by lateral movement of said roller.
7. In a machine of the class described, the combination of a cylindrical drum rotary about a horizontal axis, a tank for containing cleaning liquid around the lower portion of said drum, brushing means adjacent said drum, and devices for mounting a shade roller on said drum with a shade attached to said roller, with said shade extending from said roller around said drum for cleaning by said brushing means, said roller having end bearing supports, and said mounting devices engaging said roller end supports to hold said roller on said drum.
8. In a machine of the class described, the combination of a cylindrical drum rotary about a horizontal axis, a tank for containing cleaning liquid around the lower portion of said drum, brushing means adjacent said drum, and devices for mounting a shade roller on said drum with a shade attached to said roller, with said shade extending from said roller around said drum for cleaning by said brushing means, said brushing

means comprising a rotary brush extending longitudinally of said drum, and gearing for driving said brush by rotation of said drum, said roller having end bearing supports, and said mounting devices engaging said roller end supports to hold said roller on said drum.

9. In a machine of the class described, the combination of a cylindrical drum rotary about a horizontal axis, a tank for containing cleaning liquid around the lower portion of said drum, brushing means adjacent said drum, and devices for mounting a shade roller on said drum with a shade attached to said roller, with said shade extending from said roller around said drum for cleaning by said brushing means, said drum having a longitudinal side depression containing said mounting devices, said depression having an open side freely admitting said roller by lateral movement of said roller.

10. In a machine of the class described, the combination of a cylindrical drum rotary about a horizontal axis, a tank for containing cleaning liquid around the lower portion of said drum, brushing means adjacent said drum, and devices for mounting a shade roller on said drum with a shade attached to said roller, with said shade extending from said roller around said drum for cleaning by said brushing means, said mounting devices comprising substantially parallel guide bars carried by and extending longitudinally of said drum, blocks mounted for sliding movement on said bars for engagement with the ends of said roller, and clamping devices for holding said blocks in desired positions on said bars.

11. In a machine of the class described, the combination of a cylindrical drum rotary about a horizontal axis, a tank for containing cleaning liquid around the lower portion of said drum, brushing means adjacent said drum, and devices for mounting a shade roller on said drum with a shade attached to said roller, with said shade extending from said roller around said drum for cleaning by said brushing means, said mounting devices comprising substantially parallel guide bars carried by and extending longitudinally of said drum, blocks mounted for sliding movement on said bars, and clamping devices for holding said blocks in desired positions on said bars, one of said blocks having an aperture for receiving one end support of a shade roller, a second one of said blocks having an aperture for receiving the other end support of said shade roller, and springs between said second block and a third one of said blocks, said clamping devices cooperating with said first and said third blocks.

12. In a machine of the class described, the combination of a cylindrical drum rotary about a horizontal axis, a tank for containing cleaning liquid around the lower portion of said drum, brushing means adjacent said drum, and devices for mounting a shade roller on said drum with a shade attached to said roller, with said shade extending from said roller around said drum for cleaning by said brushing means, said mounting devices comprising substantially parallel guide bars carried by and extending longitudinally of said drum, blocks mounted for sliding movement on said bars, and clamping devices for holding said blocks in desired positions on said bars, one of said blocks having an aperture for receiving one end support of a shade roller, a second one of said blocks having an aperture

for receiving the other end support of said shade roller, and springs between said second block and a third one of said blocks, said clamping devices cooperating with said first and said third blocks, said drum having a longitudinal side depression containing said guide bars and said

blocks, said depression having an open side freely admitting said roller by lateral movement of said roller.

PETER F. NARDULLI.
